ATTORNEY

UNITED STATES PATENT OFFICE

GEORGE F. MATTESON, OF ROCKYHILL, CONNECTICUT, ASSIGNOR TO THE F. B. SHUSTER COMPANY, OF NEW HAVEN, CONNECTICUT, A CORPORATION OF CONNECTICUT

FEEDING DEVICE

Application filed November 21, 1927. Serial No. 234,734.

My invention relates more especially to that class of feed devices that are employed for operation upon material of indefinite length to feed it for various purposes, the apparatus being especially suitable for the purpose of feeding wire in connection with wire straightening and similar machines, and an object of my invention, among others, is the production of a feed device that shall be simple in construction and particularly efficient in operation.

One form of device embodying my invention and in the construction and use of which the objects herein set out, as well as others, may be attained, is illustrated in the accompanying drawings, in which—

Figure 1 is a view in side elevation of my improved feeding device, with parts broken away to show construction.

Figure 2 is a top view of the same.

Figure 3 is a view in section on a plane denoted by the dotted line 3—3 of Figure 1.

Figure 4 is a detail isometric view illustrating a fragment of a sprocket wheel and a portion of a chain disconnected therefrom.

My improved feeding mechanism illustrated and described herein embraces means for effecting a continuous steady movement of material, as an indefinite length of wire stock, particularly of the larger dimensions, although not necessarily restricted in its use to such, which mechanism includes a driving shaft 5 having means, as a driving pulley 6, for imparting rotation thereto. A supporting shaft 7 is mounted in somewhat close proximity to the driving shaft, and sprocket wheels 8—9 are supported by said shafts, one sprocket wheel being secured to the driving shaft to be driven thereby.

A feeding member 10, in the form of a sprocket chain, is supported upon and engages with the teeth of the sprocket wheels in a manner similar to structures of this class. This chain, however, is of particular construction and comprises main or gripping links 11

and connecting links 12 comprised in the feeding member 10. The gripping links are arranged in pairs located side by side, which pairs are connected by pairs of connecting links 12, the members of which are preferably located outside of the gripping links. Pins 13 are arranged to pivotally secure the meeting ends of the main and connecting links.

The ends of each pair of gripping links 55 opposite the pins 13 are provided with gripping jaws 14 projecting outwardly, preferably substantially at right angles to the main part of the link, these jaws on each pair of links being oppositely disposed and formed 60 to grip material, as a length of wire 15, between them. Clamp screws 16 are engaged within threaded openings in that end of each member of each pair of links 11 from which the jaws 14 project, these clamp screws being oppositely threaded, that is each having a left and a right hand screw thread, and the threaded openings in the links, of course, being correspondingly oppositely threaded.

The clamp screws 16 are formed, preferably near their ends, with non-circular portions 17 that are received in holes of corresponding shape in the ends of the links 12. In the construction herein shown said portions 17 and the corresponding holes are flattened on opposite sides. This construction causes the connecting links to act as levers to turn the screws 16 in the threaded openings in the gripping jaws 11, thereby effecting opening and closing movements of said 75 jaws.

In the construction shown herein, referring to Figure 1, the threads on the clamp screws are so formed that as the chain members successively arrive at the upper part of 85 the sprocket wheel 9 at the left and change their direction of movement from a curved path described by the sprocket wheel to the straight path between the two wheels, the links 12 will operate to turn the feed screws 20

in a direction to close the gripping jaws, and thereby grip a length of wire 15, and as the link members leave said straight path, at the upper part of the sprocket wheel 8 located at the right in Figure 1, and enter the curved path around said wheel the feed screws will be partially rotated in an opposite direction to that just described and the jaws 14 will be opened and the wire 15 will thereby be released. A similar movement of the jaws will take place at the bottoms of each of said sprocket wheels, but in the arrangement herein shown this operation at these points is of no consequence.

15 The gripping links 11 are each provided with supports 18 that coact to resist the force put upon said jaws in gripping an article between them. In the structure shown these supports project from the links in a direction opposite to that in which the jaws project, the ends of these supports being formed to abut one against the other. These supports pass along grooves 19 formed in the peripheries of the sprocket wheels and preferably cutting through the teeth 20 thereof, that is, the teeth are arranged in pairs, the members of each pair being located on opposite sides of the groove.

20 In accordance with the provisions of the patent statutes I have described the principles of operation of my invention together with the apparatus which I now consider to represent the best embodiment thereof; but I desire to have it understood that the apparatus shown is only illustrative and that the invention may be carried out by other means and applied to uses other than those above set out.

I claim—

40 1. A feed device including a pair of gripping jaws, means for imparting feeding movement to said jaws, means carried by said jaws for solely effecting closing movement thereof, and means effective by the feeding movement of said jaws to operate said jaw closing means.

2. A feed device including a pair of gripping jaws, means for imparting feeding movement to said jaws, means rotatably mounted for closing said jaws, and means effective by reason of the feeding movement of said jaws to swing said jaw closing means on its pivot to operate said jaws.

3. A feed device including a pair of gripping jaws, means for imparting feeding movement to said jaws, a feed screw engaged with threaded holes in said jaws, a lever secured to said feed screw, and means effective by the movement of said jaws to operate said lever.

4. A feed device including jaw members comprising a pair of gripping jaws, said members being mounted to move in relatively angularly disposed paths, means for imparting movement to said jaws along said

paths, means for closing said jaws, and means effective by reason of the change in direction of movement of said jaws to operate said jaw closing means.

5. A feed device including a pair of gripping jaws, a circular rotatably mounted member to support said jaws about its periphery, a clamp screw to close said jaws, a lever secured at one end to said clamp screw, and means for retaining the other end of said lever substantially in a circular path corresponding to that of the periphery of said supporting member, until after said jaws have passed beyond said supporting member.

6. A feed device including a supporting wheel, a feeding member supported by said wheel and including a pair of gripping links and a pair of connecting links, a feed screw engaged with threaded openings in said gripping links, and means for securing a connecting link to said feed screw to rotate the latter.

7. A feed device including a toothed supporting wheel rotatably mounted and a chain composed of links to engage said teeth, said chain including a pair of gripping links having gripping jaws, a pair of connecting links, a feed screw engaged with threaded openings in said jaws, and means for securing a connecting link to said feed screw.

8. A feed device including a rotatably mounted toothed supporting wheel, a chain extending about said wheel and composed of pairs of gripping links having gripping jaws, connecting links for connecting the pairs of gripping links, a feed screw engaged with threaded openings in said gripping links, and means for securing a connecting link to each of said feed screws.

9. A feed device including a rotatably mounted toothed supporting wheel, a feed chain supported about the periphery of said wheel and including pairs of gripping links with gripping jaws thereon, connecting links for connecting adjacent pairs of gripping links, said connecting and gripping links being arranged for engagement of said teeth between them, a feed screw engaging a threaded hole in each pair of gripping links, and means for securing a connecting link to each of said feed screws.

10. A feed device including a rotatably mounted toothed supporting wheel having a peripheral groove, a feed chain supported about the periphery of said toothed wheel and including a pair of gripping links having gripping jaws, a feed screw engaged with threaded holes in said links, supports projecting from said jaws into said groove in said wheel, said chain also including a connecting link, and means for securing said connecting link to said feed screw.

11. A feeding device including a plurality of pairs of gripping jaws, means for imparting feeding movement to said jaws, and

means actuated by reason of a change in relative positions of said pairs of jaws for effecting opening and closing movements thereof.

12. A feeding device including a plurality of pairs of gripping jaws pivotally united, means for imparting feeding movement to said jaws, and means actuated by reason of an angular change in the relative positions of said pairs of jaws for effecting opening and closing movements thereof.
